DAMPER CONTROL MECHANISM

Anthony Fraga, Brooklyn, N.Y., assignor to Slant/Fin Radiator Corporation, Richmond Hill, N.Y., a corporation of New York

Filed Dec. 20, 1962, Ser. No. 246,114

7 Claims. (Cl. 98—106)

The present invention relates to mechanism for adjusting radiator dampers and the like. While the invention is disclosed with particular reference to its application to dampers for radiators, and while the invention has particular merit in that application, broader applications and adaptations will be readily apparent to those skilled in the art so that the illustrative disclosure of the preferred embodiment should not be regarded as limiting.

An object of this invention resides in novel means for control or adjustable positioning of dampers, more specifically in novel control means for radiator dampers which, in use, is subjected to a wide range of temperatures.

A common form of radiator damper involves a horizontally hinged elongated damper that can be moved to various relatively open or closed positions by a manually operated damper control rod. In that form of radiator damper, the control rod has a helical drive element on a shaft in the radiator enclosure that cooperates with a slot in a sheet-metal part of the damper. The weight of the damper is often considerable. As a consequence, when the damper has been raised to an adjusted opening and the knob of the damper control rod is released, the helical control rod of the damper is caused to spin by the weight of the damper as the damper drops out of its adjusted position. Further, the helical control rod is sometimes unknowingly forced after the damper (normally concealed within the radiator housing) has reached a limiting extreme position. The cooperating portions of the helical control rod and the slot in the damper are then "stripped" or deformed out of effective mating contact.

Accordingly, a further object of the invention resides in the provision of a novel damper control that is largely, if not wholly, immune to the foregoing defects.

In carrying out the foregoing objects, a preferred embodiment of the invention has been produced which includes a control rod rotatably mounted in the enclosure for cooperation with a portion of the damper. The control rod in this embodiment is formed of a bar or strip of metal that is twisted so as to have two opposite helical edges. This rod works in a slot in a plastic part carried by the damper. If the damper is blocked at either extreme of its adjustment range, the shaft could still be forced without damaging its cooperating plastic part. Furthermore, the plastic part and the helical rod are in tight gripping contact so that the control rod is gripped at all times and prevented from self-rotation due to the weight of the damper. This result is achieved without resort to close tolerances or supplemental frictional structures.

The nature of the invention, together with the above and further objects and features of novelty, will be more fully appreciated from the following description of the presently preferred but illustrative embodiment which is shown in the accompanying drawings forming part of this disclosure. In the drawings:

FIGURE 1 is a perspective view of an embodiment of the invention, parts being broken away and shown in cross-section;

FIGURE 2 is a vertical cross-sectional view of the embodiment in FIGURE 1, drawing to much larger scale;

FIGURE 3 is a rear elevation of a portion of the damper in FIGURES 1 and 2; and

2

FIGURE 4 is an enlarged detail, partly in section, of a portion of FIGURES 1 and 2.

Referring now to the drawings, there is shown the top portion of a radiator housing, including a top panel 10 and a front panel 12. A damper 14 is supported on a hinge 16 near the top of panel 12. A large number of louvers 18 of conventional form are provided in the front panel 12, this panel being slit longitudinally and the slit elements being bent out of the plane of the front panel.

Within enclosure 10, 12 and ordinarily below damper 14 and louvers 18 is a radiator unit (not shown) that provides an apertured area for a rising current of heated air. This air current can emerge from louvers 18, but only if damper 14 is open. The maximum opening is represented by the dotted-line position 14' in FIGURE 2. Position 14' is reached when the damper strikes the rear of the enclosure or any other stop means (not shown). When the damper is closed, the flow of hot air is blocked.

For the purpose of adjusting the degree of opening of damper 14, the following improved mechanism is provided.

To the rear of damper 14, there is secured a three-part assembly including a sheet of plastic 20 that is confined between two metal frame members 22 and 24. These metal members overlie the marginal portions of members 20, and they extend laterally outward of the edges of plastic element 20. They are welded together, and further they are secured by a suitable means (not shown) to damper 14. Member 24 includes a raised formation which provides a sort of pocket that accommodates the thickness of plastic element 20 and locates that element against lateral shift, either vertically or horizontally, relative to the face of damper 14.

Element 20 has a slit 20a that is quite long and relatively narrow. Member 22 has an opening 22a that is larger in both directions than slit 20a. Correspondingly, element 24 has an opening 24a behind element 20 and framed about slit 20a.

A damper control rod 26 penetrates opening 20a of plastic member 20. Control rod 26 is made of an initially flat strip or bar of metal that is twisted into a double-edged helix, which may be called a twist operator. As seen in FIGURE 3, the rod 26 that was an initially flat strip retains relatively wide surfaces after the strip is twisted, and the edges of the strip become helical edges. A highly effective helical pitch is illustrated, in which a 180-degree twist measured along the rod is a little larger than the maximum transverse dimension of the rod. Rod 26 is mounted rotatably in an internally threaded piece 28 that is welded to panel 12. Externally threaded bushing 29 extends through panel 12 and into piece 28. Shaft 26 has a necked-down end portion 26a that extends rotatably through bushing 29 and into knob 30, where it is locked as by means of a conventional set screw.

The thickness of rod 26 is approximately equal to the width of slit 20a. The edges of the slit 20a grip and squeeze against the helically contoured opposite wide faces of damper control rod 26. The adjoining portions of plastic element 20 are deformed somewhat by the helical or twisted shape of member 26. Because of this relationship, there is a tight binding grip that is exerted on shaft 26 by member 20.

Slit 20a is long enough so that shaft 26 is received in that slit in both of the extreme positions 14 and 14' to which the damper can be adjusted. When the damper is in its solid-line position of FIGURE 2, the helical rod 26 is at the top of slit 20a, and when the damper is in its extreme position 14', helical rod 26 engages member 20 at the bottom of slit 20a. In intermediate conditions of adjustment between the positions 14 and 14', helical rod 26 engages intermediate portions of slit 20a. Knob 30 is used for manual adjustment of damper 14 from

either of the extreme positions illustrated in FIGURE 2 to the other and to any intermediate position.

When the damper has reached either extreme condition of its adjustment, it is possible that the person who is operating the damper might not realize this fact and he might continue—forcibly—to rotate the operating knob. In comparable known apparatus employing a round shaft carrying a helical wire secured to the shaft, the shaft and wire working in a slot in the sheet-metal of which the damper is formed, there was always the danger of "stripping" the drive relationship of the helical wire and the sheet-metal edges of the slot. The sheet-metal edges tend to spread out of effective working contact with the helical wire in the prior arrangement. After that had occurred, the reverse operation of the knob, particularly in attempting to move the damper from its vertical, depending position to a raised position, would be ineffectual.

When either extreme position of adjustment has been reached with the novel damper control arrangement described above and shown in the drawings, the edges of plastic member 20 will be bearing against the wide faces of rod 26, as in FIGURE 3. Continued, forcible operation of rod 26 after the damper has reached a limit, will result in portions of member 20 being pushed or pulled out of their normal plane by the broad surfaces of twisted rod 26. As a full half-turn of rod 26 beyond the damper limit is reached, the plastic resiliently resumes the configuration in FIGURE 3. No damage results from forcible drive of the control rod beyond the point where the damper has reached a limiting position. Thereafter, reverse rotation of the damper control rod is fully effective in adjusting the damper away from that limiting position, just as if forced operation beyond the limit had not taken place.

Damper 14 is often a relatively heavy member, for it may be well over a yard long and it is made of relatively heavy-gauge sheet metal. In comparable apparatus that uses the above-mentioned known form of helical control rod working in a slot in the damper, the weight of the damper is such that there has been a strong tendency of the damper to drop from any open condition of adjustment toward its fully closed position, when the adjustment knob is released. The damper weight simply causes the control rod to spin as the damper drops. The firm grip of the plastic element 20 with the described damper control rod 26 is highly effective in holding the damper fixed in any position of adjustment to which it is moved.

Member 20 is made adequately thick for transmitting the adjustment force from rod 26 to the damper. The firmness of plastic member 20 is enhanced through most of the adjustment range by limiting the width of the slots 22a and 24a, as illustrated. The width of these openings is increased near the end limits so that rod 26 can be forced (while members 14 and 20 are arrested) without damaging member 20.

Member 20 is of any suitable plastic that is yieldable so as to act in the manner described above. As part of a radiator damper, it is of a plastic that retains its pliable, firm and resilient properties over a wide range. Polyurethane has been found to be particularly effective for this purpose. Furthermore, polyurethane is non-abrasive.

From the foregoing, it will be seen that a highly successful embodiment of the present invention has been described and shown in the accompanying drawings. Those skilled in the art will readily recognize a latitude of variation and varied applications of the novel features, and therefore the invention should be construed broadly in accordance with its full spirit and scope.

What is claimed is:

1. In combination an enclosure having a front panel having an apertured area, a damper hinged to the rear of said panel adapted to cover said apertured area and operable through an angle between open and closed limits, a damper control rod having opposite wide surfaces bounded by helical longitudinal edges, means supporting

said rod for rotation about a fixed axis, said supporting means being carried by said front panel, said means also constraining the rod against axial shift relative to said front panel, and a member of tough and resilient plastic material fixed to said damper and formed with an elongated slot generally perpendicular to the axis of the hinged damper, the slot in said plastic member receiving said damper control rod and the edges of the slot gripping said opposite wide surfaces of the control rod, and means to rotate said control rod.

5 2. In combination an enclosure having a front panel having an apertured area, a damper hinged to the rear of said panel adapted to cover said apertured area and operable through a range between open and closed limits, a 15 damper control rod having opposite wide surfaces bounded by a pair of opposite helical longitudinal edges, means supporting said rod for rotation about a fixed axis, said supporting means being carried by said front panel, said means also constraining the rod against axial shift relative to said front panel, and means secured to said damper for cooperating with said damper control rod, said means including a frame member having an opening therein, a member of tough and resilient plastic material supported by said frame member on said damper and formed with an elongated slot generally perpendicular to the axis of the hinged damper, the slot in said plastic member receiving said damper control rod and the edges of the slot gripping said opposite wide surfaces of the control rod, the opening in said frame member being only 25 a little wider than said slot and said frame member bearing against the surface of said plastic member outside said opening and thereby reinforcing said plastic member adjacent the slot, and means to rotate said control rod.

30 3. The combination in accordance with claim 1 above, wherein said plastic member is a sheet of polyurethane.

4. The combination in accordance with claim 1 wherein the width of said wide surfaces is a little smaller than one-half of the helical pitch of said longitudinal edges of the rod, and wherein said plastic member is a sheet disposed transverse of said rod and the thickness of the plastic sheet being only a small part of one-half helical pitch.

45 5. In combination an enclosure having a louvered panel, a damper panel mounted behind said louvered panel and arranged to be moved between open and closed limits of adjustment, a damper control rod rotatably secured to one of said panels, said control rod having a pair of opposite relatively wide surfaces bounded by a pair of opposite helical longitudinal edges, a member of tough resilient plastic material secured to the other of said panels and having a slot whose edges receive and tightly grip said relatively wide surfaces of the control rod, and means to rotate said control rod.

50 6. In combination an enclosure having a vent opening therein, a damper operable through a range between open and closed limits relative to said opening, a damper control device mounted rotatably in said enclosure, and means secured to said damper and cooperating with said control device to operate said damper through said range, said damper control device including a long-pitch helical-edged portion and said cooperating means including an apertured member of a tough, resilient plastic gripping said long-pitch helical-edged portion, the thickness of said plastic member measured along said helical-edged portion being only a small part of one-half the helical pitch.

65 7. In combination an enclosure having a vent opening therein, a damper operable through a range between open and closed limits relative to said opening, a damper control device mounted rotatably in said enclosure, and means secured to said damper and cooperating with said control device to operate said damper through said range, said damper control device including a long-pitch helical-edged portion and said cooperating means including a

tough, resilient plastic sheet disposed transverse to said helical-edged portion and said plastic sheet having a slot therein constituting a pair of relatively movable edges squeezed against opposite sides of said helical-edged portion.
